UNITED STATES PATENT OFFICE.

JOSEPH MAZER, OF McALESTER, OKLAHOMA.

WINDING-INDICATOR.

1,108,508.

Specification of Letters Patent. Patented Aug. 25, 1914.

Application filed April 21, 1911. Serial No. 622,584.

To all whom it may concern:

Be it known that I, JOSEPH MAZER, a citizen of the United States, and resident of McAlester, in the county of Pittsburg and 5 State of Oklahoma, have invented a new and useful Improvement in Winding-Indicators; and I do hereby declare the following to be a full, clear, and exact description thereof.

My invention relates to a winding indicator to be used in connection with watches, 10 clocks, phonographs or other devices to which it may be found applicable, whereby it is possible by a dial located in view and an indicator hand to tell to what extent the 15 main spring is wound, so that the observer may know not only when the spring is fully wound or when it has run down, but also the extent to which it is wound at any particular moment and the time when it will 20 require rewinding. I have already had several patents issued to me relating to these winding indicators, one of said patents being No. 790,508, granted May 23, 1905, and the purpose of my present invention is 25 to improve such construction set forth in said patent in certain ways, so as to provide a simpler form of mechanism with fewer parts, while at the same time the parts are so arranged as to make them readily accessible in 30 case of repair and so inclosed as to give a practically dust proof construction.

Other objects of my invention will appear as the invention is disclosed later in the specification, the above being merely a 35 general statement of some of the main objects of said invention.

My invention comprises the features hereinafter set forth and claimed.

In the drawings Figure 1 is a face view 40 of a watch showing my invention applied thereto; Fig. 2 is an enlarged diagrammatic view; Fig. 3 is an enlarged section on the line 3—3 Fig. 2; Fig. 4 is an enlarged plan view of a portion of the rear face; Fig. 5 is a 45 detail of one of the gears carrying the planetary gear; and Fig. 6 is a modified form of my invention.

In the drawing I have illustrated my invention as applied to the dial A of a suitable watch with the bottom plate B, which 50 is provided with the recess C for the reception of the parts hereinafter set forth.

The main-spring barrel *a* has the pinion *b* formed integral therewith or attached 55 thereto in any suitable manner, said pinion meshing with the gear-wheel *d*. The gear-

wheel *d* is mounted loosely on the bearing *g'* of the double pinion *g* mounted on the shaft or pin *g*². The pinion *g* extends up through an opening in said wheel *d*. Below the bearing *g'* is a shoulder *g*⁴ which engages the wheel *d* and holds said gear in place. The pin *g*² has a journal or neck *g*³ which fits in a bearing in the plate B. Secured to the gear-wheel *d* by the screw *e'* is the double planetary gear *e* provided with the teeth *e*² and *e*³. The teeth *e*³ of the planetary-gear *e* mesh with the teeth *g*⁵ on the pinion *g*. The gear-wheel *c* is mounted on the shaft *g*² and said gear-wheel has the pinion *f* which 60 meshes with the teeth *e*² of the planetary-gear *e*. The gear-wheels *d* and *c* are dished or recessed so as to provide a space *c'* between the same for the reception of the planetary-gear *e*, as well as the inner portion 65 of the pinion *g* and the pinion *f*. The outer edges of the gear-wheels *c* and *d* are provided with the flanges *c*² which bear against each other so that when the gear-wheels *c* and *d* are arranged as shown in 70 Fig. 3, a practically dust proof casing is provided for the parts contained within the space *c'* inclosed by said wheels, while at the same time by said construction, I am enabled to make a more compact arrangement and thereby reduce the space required 75 for the parts as more fully hereinafter set forth. The teeth *c*³ on the gear-wheel *c* mesh with the pinion *l*' secured to the shaft *l*² which is journaled in the plate B. At 80 the upper end of the shaft *l*² is the gear-wheel *l* which meshes with the ratchet-wheel *k*, which in turn meshes with the gear-wheel *m*. The gear-wheel *m* meshes with the gear-wheel *n*, loosely mounted on a 85 screw *n*' through which the shaft *o* passes which carries the indicator hand *r*. The gear-wheel *n* has the bevel gear *n*² which is engaged by the bevel pinion *s* on the winding shaft *s*'. Secured to the lower end of 90 the shaft *o* is the gear-wheel *i* which meshes with the gear-wheel *h*. This gear-wheel *i* will be referred to in the claims as the indicator-hand wheel. This gear-wheel *h* in 95 turn meshes with the teeth *g*⁶ of the pinion *g*. The plate J is secured to the watch-plate by the screws J' and covers up the gear-wheels *i*, *h* and *g* so that dust and dirt is excluded.

The operation is as follows: Let us assume 110 that the watch is run down and that it is to be wound up. In this case the indicator

hand *r* will be pointing toward the word "wind" on the dial of the indicator. By turning the winding-shaft *s'*, the gear-wheel *n* is rotated and through it the gear-wheel *m*. Rotary motion is imparted to the ratchet-wheel *k* by gear-wheel *m* and from the ratchet-wheel *k* to the gear-wheel *l*. The pinion *l'* on the shaft *l'* imparts rotary motion to the gear-wheel *c*, which in turn, through the pinion *f* imparts rotary motion to the planetary-gear *e*. The teeth *e'* of the planetary-gear engage the teeth *g'* of the pinion *g*. The teeth *g'* of the pinion *g* meshing with the gear-wheel *h* drives said gear-wheel and through it the gear-wheel *i* on the indicator shaft *o*. In this manner the reverse movement is imparted to the indicator shaft *o*. At the same time the winding of the watch is accomplished, the ratchet-wheel *k* being mounted on the barrel-arbor *t* which carries the main-spring barrel *a*.

When the watch is unwinding the power to operate the indicator-finger *r* comes from the unwinding of the main-spring barrel *a*, through the pinion *b* engaging the gear-wheel *d*, said gear-wheel carrying the planetary-gear *e* which in turn meshes with double pinion *g*. The pinion *g* meshes with *h* which meshes with *i* carrying an indicator hand.

By connecting the gear-wheel *d* to the small pinion *b* instead of to the periphery of main-spring barrel *a*, I reduce the speed at the start instead of afterward reducing it by a train of gears or wheels, and I am enabled to greatly reduce the space required and simplify the construction.

Another point of advantage of my construction is that I have all the wheels which perform the actual reversing of the indicator-hand between the two wheels *c* and *d*, the one connecting to the main-spring barrel and the other to the ratchet wheel, whereby I am enabled to provide a practically dust proof arrangement and in addition to that, save the space which would be necessary to allow for clearance where one wheel was mounted on top of the other, instead of facing each other, as they do in said patent. Furthermore, by making an extra large hole in the wheel *d* and making the pinion *g* with the stud *g'* act as its own bearing, I put the watch together from the outside rather than from the inside, as was formerly the case, and by mounting of the gear-wheel *d* on the pinion *g* said gear-wheel acts as a cap to hold the wheels together. Furthermore, by having the opening in the wheel *d* large enough, the gear-wheel *d* carrying the planet-gear may be lifted off the pinion, or the pinion lifted from it without removing the screw holding down the planet-wheel.

Another important feature of my invention is that the whole indicating mechanism

is placed within a recess within the plate which when covered by the cap *J* makes the whole arrangement dust-proof and unlikely to catch dirt, in direct contrast with previous arrangements which have given free access to any dirt particles which may be about.

In Fig. 6 I have illustrated a modified form of my invention in which the double pinion *p* is a deep spur-gear which forms a bearing for wheel *u* and the upper portion of the teeth mesh with the planetary pinion *v*. The lower portion of the teeth mesh with the intermediate gear-wheel *w* connected up to the indicator hand by the gear-wheel *x*. Furthermore, the edges or flanges of wheels *u* and *u'* overlap so that the wheel *u'* also forms a bearing for the wheel *u* in addition to the bearing formed by the teeth of the double pinion *p*.

What I claim is:

1. In a watch or the like, the combination with the main-spring barrel, of a ratchet-wheel, connections between said ratchet-wheel and the winding mechanism, recessed gear-wheels forming a space between the same, connections between one of said gear-wheels and said ratchet-wheel, connections between the other gear-wheel and said main-spring barrel, and reversing gears contained within said space formed by said gear-wheels.

2. In a watch or the like, the combination with the main-spring barrel, of a ratchet-wheel, connections between the ratchet-wheel and winding mechanism, recessed gear-wheels forming a space between the same, connections between one of said wheels and said ratchet-wheel, connections between the other wheel and said main-spring barrel, a winding indicator hand, a double planetary gear carried by one of said wheels in the space between the same, and connections between said planetary-gear and said indicator hand.

3. In a watch or the like, the combination of the main-spring barrel, of a ratchet-wheel, connections between said ratchet-wheel and winding mechanism, two recessed gear-wheels forming a space between the same, connections between one of said gear-wheels and said ratchet-wheel, connections between one of said gear-wheels and said ratchet-wheel, connections between the other gear-wheel and said spring-barrel, a double planetary-gear carried by one of said gear-wheels, a double-pinion extending up into said space between said gear-wheels and engaged by said planetary-gear, said pinion having a bearing in the watch-plate, a winding indicator hand, and connections between said winding indicator hand and said double pinion.

4. In a watch or the like, the combination of the main-spring barrel, of a ratchet-

- wheel, connections between said ratchet-wheel and winding mechanism, two recessed gear-wheels forming a space between the same, connections between one of said gear-wheels and said ratchet-wheel, connections between the other gear and said spring-barrel, a double planetary-gear within said space between said gear-wheels and carried by one of said gear-wheels engaging the other of said gear-wheels, a double pinion having a bearing in the watch-plate and extending up through an opening in one of said recessed gears, and engaged by said planetary-gear, a winding indicator hand, and connections between said winding indicator hand and said double pinion.
5. In a watch or the like, the combination of a plate, a main spring barrel seated on one side thereof, a ratchet-wheel and connections therefrom to the winding mechanism on the opposite side of said plate and flush, or substantially flush, therewith, a winding indicator hand, and connections from said ratchet-wheel and main spring barrel to said indicator hand interposed between said plate and said barrel.
10. In a watch or the like, the combination of a plate, a main-spring barrel seated on one side thereof, a ratchet-wheel and connections therefrom to the winding mechanism on the opposite side of said plate and flush or substantially flush therewith, a winding indicator-hand wheel interposed between said plate and barrel, connections between said indicator-hand wheel and said ratchet wheel in winding and between said indicator hand wheel and main spring barrel in unwinding, and said plate covering said connections.
15. In a watch or the like, the combination of the main-spring barrel, a ratchet-wheel, connections between the ratchet-wheel and winding mechanism, two recessed gear-wheels forming a space between the same, a double pinion having a shoulder, a shaft on said pinion bearing in the watch-plate, one of said recessed wheels mounted on said shaft, the other recessed wheel having an opening therein through which said double pinion passes and engaged by the shoulder on said double pinion, a double planetary gear on said last named dished wheel, said first named recessed wheel engaging said planetary-gear, said pinion engaging said planetary-gear, a winding indicator hand, connections between said winding indicator hand and said double pinion, and connections between said second named recessed wheel and the main-spring barrel.
20. In a watch or the like, the combination of the main-spring barrel, winding mechanism including a ratchet-wheel, a winding indicator-hand wheel, a gear-wheel, connections between said gear-wheel and said barrel, a double pinion extending through an opening in said gear wheel and forming a bearing for same, said pinion having a shoulder engaging said wheel, connections between said pinion and said indicator-hand wheel and between said pinion and 60 said ratchet-wheel in winding, and connections between said gear wheel and said indicator-hand wheel in unwinding.
25. In a watch or the like, the combination of the main-spring barrel, winding mechanism including a ratchet-wheel, a winding indicator-hand wheel, a gear-wheel, connections between said gear-wheel and said barrel, a double pinion extending through an opening in said gear-wheel and forming a bearing for same, connections between said pinion and said indicator-hand wheel and between said pinion and said winding mechanism, and connections between said gear-wheel and said indicator hand wheel in unwinding.
30. In a watch or the like, the combination of the main-spring barrel, winding mechanism including a ratchet-wheel, a winding indicator-hand wheel, a gear wheel, 75 connections between said gear-wheel and said barrel, a pinion extending through an opening in said gear-wheel and forming a bearing for same, connections between said pinion and said indicator-hand wheel and between said pinion and said winding mechanism, and connections between said gear-wheel and said indicator hand wheel in unwinding.
35. In a watch or the like, the combination of the main-spring barrel, winding mechanism including a ratchet-wheel, a winding indicator-hand wheel, a gear wheel, 80 connections between said gear-wheel and said barrel, a pinion extending through an opening in said gear-wheel and forming a bearing for same, connections between said pinion and said indicator-hand wheel and between said pinion and said winding mechanism, and connections between said gear-wheel and said indicator hand wheel in unwinding.
40. In a watch or the like, the combination of the main-spring barrel, a ratchet-wheel, connections between the ratchet-wheel and winding mechanism, two recessed gear-wheels forming a space between the same and having overlapping edges, a double pinion extending up through an opening in one of said gear-wheels, connections between one of said gears and the ratchet-wheel, connections between the other gear-wheel and said main-spring barrel, and reversing mechanism 90 contained within the space formed by said gears.
45. In a watch or the like, the combination of the main-spring barrel, a ratchet-wheel, winding mechanism, a winding indicator hand, two recessed gear-wheels forming a space between same and having overlapping edges, a double pinion extending up through an opening in one of said gear-wheels, connections between one of said gears and the ratchet-wheel, connections between the other gear-wheel and said main-spring barrel, and reversing mechanism 95 contained within the space formed by said gears.
50. In a watch or the like, the combination of the main-spring barrel, a ratchet-wheel, winding mechanism, a winding indicator hand, two recessed gear-wheels forming a space between same and having overlapping edges, a double pinion extending up through an opening in one of said gear-wheels, connections between one of said gears and the ratchet-wheel, connections between the other gear-wheel and said main-spring barrel, and reversing mechanism 100 contained within the space formed by said gears.
55. In a watch or the like, the combination of the main-spring barrel, a ratchet-wheel, winding mechanism, a winding indicator hand, two recessed gear-wheels forming a space between same and having overlapping edges, a double pinion extending up through an opening in one of said gear-wheels, connections between one of said gears and the ratchet-wheel, connections between the other gear-wheel and said main-spring barrel, and reversing mechanism 105 contained within the space formed by said gears.
60. In a watch or the like, the combination of the main-spring barrel, a ratchet-wheel, winding mechanism, a winding indicator hand, two recessed gear-wheels forming a space between same and having overlapping edges, a double pinion extending up through an opening in one of said gear-wheels, connections between one of said gears and the ratchet-wheel, connections between the other gear-wheel and said main-spring barrel, and reversing mechanism 110 contained within the space formed by said gears.

In testimony whereof, I, the said JOSEPH MAZER, have hereunto set my hand.

JOSEPH MAZER.
